UNITED STATES PATENT OFFICE.

JOHN H. HECKER, OF LEBANON, PENNSYLVANIA.

IMPROVEMENT IN GRAPPLIES FOR HOISTING-MACHINES.

Specification forming part of Letters Patent No. 128,309, dated June 25, 1872.

To all whom it may concern:

Be it known that I, JOHN H. HECKER, of Lebanon, in the county of Lebanon and State of Pennsylvania, have invented a new and valuable Improvement in Horse Hay-Forks and Hoisting-Machines; and I do hereby declare that the following is a full, clear, and exact description of the construction and operation of the same, reference being had to the annexed drawing making a part of this specification, and to the letters and figures of reference marked thereon.

Figure 1 of the drawing is a representation of a plan view of my invention, and Fig. 2 is a detail view of the same.

My invention has relation to horse hay-forks; and consists in the construction and novel arrangement of a swivel-pulley situated at the top of the fork and used in connection with the elevating-rope, the object of the swivel being to allow the fork to be more easily managed. The novelty also consists in the construction and novel arrangement of the trip mechanism, by means of which the fork is opened to deposit its contents, all as hereinafter described.

In the drawing, A represents an upright post, capable of extension by splicing. B is a horizontal beam holding two pulleys, C C'. D is a vertical extension of said beam. E E' represent the jaws of the fork pivoted together at e. The handle or arm E² of jaw E¹ passes through a slot in the arm of the jaw E. F F' are toggles pivoted to the upper ends of arms E² E'. These toggles are forked at their upper ends and hold an oscillating block, e¹. Through this block passes the pivot e², and also through the stem e³ of a pulley-block, e⁴, which is swiveled upon said stem. The pulley-block e⁴ holds the pulley e⁵, which is, by reason of the peculiar arrangement of the block, allowed freedom of movement to adapt itself to all positions of the fork. G is the elevating-rope, which is attached to extension D, passed under pulley e⁵, thence over pulley C', and is brought down and under a pulley at H, whence it is carried to the horse.

The arm E³ is adapted to hold the trip mechanism, and is therefore enlarged, as shown in Fig. 2. The end of the toggle-arm F fits a socket or recess in the upper end of the arm E³, and is held in place by a transverse bolt, g, having its end beveled. g¹ is a spring attached to one side of a slot, g², and forked at its upper end to enter a groove in the surface of the bolt g. This spring holds the bolt in position, but allows it to retreat when the toggle is pressed against its beveled end. h represents an L-shaped lever pivoted within a recess, h'. The long arm passes through a slot in the spring, and thence outside the arm E³, and has attached to it the trip-cords i passing around pulleys i¹ i² attached to the fork, as shown. The short arm of said lever reaches toward the spring, and has the effect of pressing back the same when the cord i is pulled.

It will be seen that when the spring is pressed back the bolt g is thrown out and the toggle released. In consequence of this the fork-jaws separate and allow the load to be deposited at any place desired. When the cord is released the jaws close again, and the toggle-arm F, being placed in its recess, connects automatically with the bolt g. The block i³ of pulley i² is hung loosely, so as to adapt itself to the movements of the fork and prevent entanglement of the trip-cord.

What I claim as my invention, and desire to secure by Letters Patent, is—

1. The trip h and latch g, in combination with the hooks E E¹, substantially as and for the purpose specified.

2. The frame A B and detachable projection D, in combination with the other parts herein specified, constructed substantially as and for the purpose described.

In testimony that I claim the above I have hereunto subscribed my name in the presence of two witnesses.

JOHN H. HECKER.
